UNITED STATES PATENT OFFICE.

JAMES M. MORRIS, OF EUGENE, OREGON.

AMUSEMENT APPARATUS.

1,069,715..

Specification of Letters Patent Patented Aug. 12, 1913.

Application filed August 22, 1912. Serial No. 716,547.

To all whom it may concern:

Be it known that I, JAMES M. MORRIS, a citizen of the United States, residing at Eugene, in the county of Lane and State of Oregon, have invented a certain new and useful Improvement in an Amusement Apparatus, of which the following is a specification, reference being had therein to the accompanying drawing.

10 This invention relates to an amusement apparatus and has for its object the production of an apparatus which consists in a combination circular seesaw, giant stride, trapeze and swing.

15 The principal object of this invention is the production of a simple and efficient standard which so supports the main supporting board as to allow the different portions of the apparatus to be efficiently attached thereto.

20 Another object of this invention is the production of an efficient means for securing the main supporting board to the standard so as to allow the same to swing in the usual manner as a seesaw.

25 With these and other objects in view, this invention consists of certain novel constructions, combinations, and arrangements of parts, as will be hereinafter fully described and claimed.

30 In the drawings:—Figure 1 is a side view of the device showing the same supported upon the primary supporting standard. Fig. 35 2 is a side elevation of the device showing the supporting board used as a seesaw upon the auxiliary supporting frame. Fig. 3 is a top plan view of the device as illustrated in Fig. 2. Fig. 4 is a transverse section taken on line 4—4 of Fig. 2. Fig. 5 is a 40 transverse section taken on line 5—5 of Fig. 3.

45 By referring to the drawings it will be seen that the main or primary standard comprises a plurality of corner vertically extending members 1 which are connected at their lower ends by means of the cross members 2. Laterally extending V-shaped brace members 3 are secured near the corners of the primary standard, and the vertical members 1 of the standard are also braced by means of auxiliary braces 4 and 5. Cross braces 6 are also employed for bracing the standard and constituting an efficient support therefor. The upper ends of the

55 side members 1 of the standard are connected by means of transversely extending brace members 8, as illustrated in Fig. 1.

When it is desired that the device be used as a trapeze or swing or giant stride, the auxiliary frame 9 is placed upon the primary frame as indicated in Fig. 1. This auxiliary frame comprises a pair of corner standards 10 which are braced by means of transversely extending connecting members 11, which transversely extending connecting members 11 engage the sides of the upper end of the primary standard as indicated in Fig. 1, so as to have its overhanging ends fit over the transversely extending members 8 of the primary standard. In 70 this manner it will be seen that the auxiliary standard will be firmly held upon the primary standard and that the same will be placed upon the primary standard by sliding the same over the upper end of the primary standard. The lower ends of the corner standards 10 are braced as at 12 to fit over the upper end, as illustrated in Fig. 1, of the primary standard. These braces will, therefore, constitute an efficient lock for 75 bracing the auxiliary standard upon the primary standard. The vertically extending members 10 of the auxiliary standard are braced by means of cross braces 13, and these vertically extending members 10 support the top plate 14.

80 A bearing plate 15 is secured to the upper face of the top plate 14, and this bearing plate is provided with a race 16 for receiving the ball bearing 17. A hinge plate 18 is pivotally secured to the top plate 14, and is held above the bearing plate 15, by means of a journal bolt 19, which bolt passes through the hinge plate 18, and is securely held in engagement with the top plate 14 85 by means of a nut 20. The hinge plate 18 is provided with a pair of pintle receiving ears 21, which are spaced from the side edges thereof, and are spaced from each other so as to allow the head of the bolt 19 to fit therebetween. An auxiliary hinge plate 22 is carried by the under face of the seesaw board 23, and this plate is provided near each end with a pintle receiving ear 24 for receiving the pintle pin 25. This 90 100 105 pintle pin is held in the ears 21 and 24, by means of the nut 26.

Handles 27 may be adjustably secured

along the see-saw board 23, and these handles comprise a pair of parallel members 28 which are connected at their upper ends, by means of a transverse bar 29. The lower ends of these parallel members 28 are notched as indicated at 30, for firmly gripping around the side edges of the see-saw board 23. A binding bolt 31 is secured to the lower ends of the parallel members 28, 35 and firmly hold the notches 30 around the edges of the see-saw board 23. It will, therefore, be seen that the handles 27 may be adjustably secured at any desired position along the see-saw board, as indicated at 40 Figs. 1 and 2. From the foregoing description, it will be seen that the handles 27 may be adjusted upon different places along the see-saw board so as to allow different weight persons to balance the board when so desired. By having the handles adjusted in this manner, it will be seen that the handles may be moved to a convenient place for the occupant of one end of the board to hold securely thereto, as for instance, where a 45 heavy person is seated upon the board to one side of the center thereof, the handle 27 may be moved up near the center of the board so as to allow the heavy person to be seated near the center thereof, and when a lighter person is seated upon the opposite end of the board the handle 27 upon this end will be moved out toward the end so as to allow the light person to be seated upon the extreme end of the board to balance the 50 heavy person who is moved a relative distance toward the center of the board to secure the desired balance. Bumper members 32 are carried by the under face of the auxiliary hinge plate 22 to take up the jar of the board, as the same swings while being used as a see-saw.

Eyes 33 are secured to the respective ends of the see-saw board 23, and to these eyes may be secured the trapeze 34, or the usual 55 swing 35. The giant stride 36 is suspended upon the suspending rod 37, from the chain 38, which chain is supported upon some of the eyes carried by the under face of the see-saw board.

From the foregoing description, it will be seen, that a very efficient and durable device has been produced which may be adjusted to accommodate different amusement apparatuses and which may be effectively 60 operated so as to rotate when so desired or so as to swing in the usual manner as is the case with a see-saw.

It, of course, should be understood that the see-saw may be used when the auxiliary standard is removed from the primary standard when it is so desired, especially where the see-saw board is being used by small children. When it is desired to swing 65 a trapeze or other suspended device from the board the same effect of the swinging

board may be produced by placing the auxiliary standard upon the primary standard, so as to raise the see-saw board to a great height and allow the amusement device to be hung or swung therefrom.

What is claimed is:—

1. An amusement apparatus of the class described comprising a primary standard and an auxiliary standard, said auxiliary standard detachably secured to said primary standard, a top plate carried by said auxiliary standard, a bearing plate carried by said auxiliary standard, ball bearings carried thereby, a hinge plate pivotally secured to said top plate and bearing plate, pintle receiving ears carried by the center of said hinge plate and spaced from the side edges thereof, an auxiliary hinge plate provided with pintle receiving ears registering with the pintle receiving ears of said primary plate, a see-saw board carried by said auxiliary hinge plate, and means passing through said pintle receiving ears for pivotally securing said hinge plates together, whereby said see-saw board may be swung upward and 90 downward.

2. An amusement apparatus of the class described comprising a primary standard and an auxiliary standard detachably secured thereto, a see-saw board pivotally secured to said auxiliary standard, adjustable handles carried by said see-saw board and comprising parallel side members provided with notches formed therein, said notches adapted to fit over the side edges of said see-saw board, a connecting rod secured to the upper ends of said parallel side members and a binding rod connecting the lower ends of said side members for firmly holding said side members in engagement with said see-saw board whereby said handle will be held firmly in an adjusted position upon said see-saw board.

3. An amusement apparatus comprising a primary standard consisting of a plurality of vertically extending side members, transversely extending braces engaging said side members, cross braces engaging said side members for reinforcing the same, an auxiliary standard provided with side members having notched lower ends, transversely extending supporting braces carried by said primary standard, said notched lower ends adapted to fit over said transversely extending supporting braces, transversely extending supporting braces carried by said auxiliary standard, a brace upon the upper end of said primary standard for holding said auxiliary standard upon said primary standard, said primary standard being open at 115 one side to allow said auxiliary standard to be inserted therein, and an amusement device supporting member carried by said auxiliary standard.

4. An amusement apparatus of the class

described comprising a primary section and an auxiliary section, said sections tapering toward their upper ends, rest supports formed upon said primary section, and said auxiliary section adapted to slip under the upper edge of said primary section and rest upon said supports so that said auxiliary section will be supported in an efficient manner upon said primary section, and a ro-

tary amusement device secured to said auxiliary standard.

In testimony whereof I hereunto affix my signature in presence of two witnesses.

JAMES M. MORRIS.
